DRYER FRAME

Anton W. Pfeffer, Spokane, Wash.

Application September 26, 1945, Serial No. 618,628

5 Claims. (Cl. 211—177)

1

This invention relates to a clothes rack and it is one object of the invention to provide a clothes rack formed of bars of wood or other suitable material which may be easily assembled to form the rack or taken apart, the bars being so formed that when they are assembled they will be interlocked and form a rigid rack which will be very sturdy and not liable to accidentally come apart.

Another object of the invention is to provide a rack formed from straight bars having special joints for holding them in engagement with each other when assembled.

Another object of the invention is to provide a rack which is simple in construction and may be manufactured at small cost.

The improved clothes rack is illustrated in the accompanying drawings wherein:

Fig. 1 is a perspective view of the clothes rack.

Fig. 2 is a showing of the manner in which an end of the upper rail is connected with the upper end of a standard.

Fig. 3 is a view showing the manner in which the lower rail is supported by the standards.

Fig. 4 is a perspective view of an end portion of the upper rail.

Fig. 5 is a perspective view of a portion of one of the cross bars of the base.

Fig. 6 is a fragmentary sectional view taken along the line 6—6 of Figure 1.

Fig. 7 is a perspective view of an end portion of one of the longitudinally extending bars of the base.

This improved clothes rack has a base consisting of longitudinally extending bars 1 and cross bars 2 at its ends. The cross bars 2 are each formed with slots 3 leading from their upper edge faces to receive end portions of longitudinally extending bars and each has its inner side face formed with a recess extending its full depth between the slots 3. The longitudinally extending bars 1 are formed near their ends with recesses or grooves 5 and 6 in their outer and inner side faces extending their full depth, and referring to Figure 6 it will be seen that when the end portions of the longitudinally extending bars 1 are fitted into the slots 3 of the cross bars 2 portions of the cross bars bordering the slots 3 fit into the recesses 5 and very effectively form a lock to prevent the cross bars from slipping along the longitudinally extending bars and out of engagement with ends thereof. It should also be noted that the inner recesses 6 are disposed at opposite sides of the recesses 4 of the end bars 2 so that when lower ends of standards 7 are thrust downwardly between the longitudinally extending bars

of the base they will fit into the recesses 6 as well as fitting into the recesses 4. This causes the standards to be firmly held against movement out of flat contacting engagement with the end bars 2 and also causes the standards to assist in holding the bars 1 and 2 in interlocked engagement with each other. When the standards are withdrawn the bars 1 and 2 may be easily taken apart for disassembling the rack.

10 The standards 7 may be of any height desired and intermediate its height each is formed in its inner side face with a groove 8 which extends transversely of the standard from one edge face thereof and has its inner end portion deepened to form a seat 9 extending downwardly below the lower edge of the groove or recess 8. A rail 10 extends between the standards and ends of the rail are thrust into the recesses 8 through open ends thereof and then pressed downwardly into 15 the seats 9 so that they can not accidentally move out of engagement with the standards by slipping through the grooves or recesses 8 towards open ends thereof. While one rail 10 has been shown it will be understood that additional rails may be provided if so desired. Grooves 11 are formed across the upper face of the rail so that when hooks of wire hangers are engaged across the rail they may fit into the grooves and hold the hangers spaced from each other. After the rail 10 has 20 been applied an upper rail 12 is applied. This rail 12 fits into recesses 13 formed at upper ends of the standards and adjacent each end the rail 12 is formed with a side recess 14 to accommodate a portion of the standard bordering the recess 13 25 into which the rail 12 fits. The rail 12 is of greater length than the rail 10 and when ends of the rail 12 are fitted into the recesses 13 it is necessary to spring the standards towards each other and move them from the position indicated by dotted 30 lines in Figure 1 to the position shown in full lines. It will thus be seen that the standards will be held under tension and pressed against ends of the rail 10 so that the rail 10 will have its ends firmly held in the seats 9 at inner ends of the 35 grooves 8 and binding action will take place which will very effectively prevent the rail 10 from being accidentally shifted upwardly out of the seats 9. When the rail 12 is removed from the grooves 13 the standards will spring apart and pressure upon 40 ends of rail 10 will be relieved so that the bar 10 may be easily removed and the standards drawn upwardly from between the longitudinally extending bars of the base. Grooves 15 corresponding to the grooves 11 are formed across the upper 45 face of the rail 12 to receive hooks of wire hangers 50 55

and hold the hangers spaced from each other when applied to the rail 12. When the clothes rack is assembled it will be very sturdy and not be liable to come apart or become rickety but when it is desired to take it apart this may be very easily done and the bars and rails tied in a bundle and placed upon a shelf until again needed. This also permits the clothes rack to be packed in a small box and sold to a customer in knocked down condition and easily assembled for use by the purchaser.

Having thus described the invention, what is claimed is:

1. A clothes rack comprising a base having longitudinally extending bars and cross bars, the cross bars being formed with slots leading from their upper edge faces and having inner side faces formed with vertical recesses between the vertical slots, the longitudinally extending bars having end portions fitting into the slots of the cross bars and formed with outer vertical recesses receiving portions of the cross bars and inner recesses, vertical standards having lower portions fitting snugly between the longitudinally extending bars and engaged in the recesses found in inner faces of the cross bars and the longitudinally extending bars and holding the standards and the bars in interlocked engagement with each other, said standards having recesses leading from their upper ends and each being formed intermediate its height with a recess in its inner side face extending transversely thereof and having its inner end portion deepened to form a seat, a rail extending between said standards with its ends fitted into the recesses in the inner side faces of the standards and seated in the deepened inner ends thereof, and an upper rail extending between upper ends of the standards and engaged in the recesses leading from upper ends thereof, said upper rail having the end portions thereof formed with side recesses for receiving portions of the standards, for holding the upper rail and the standards interlocked with each other.

2. A clothes rack comprising a base having longitudinally extending bars spaced from each other and cross bars, the cross bars having vertical slots leading from their upper edge faces and vertical recesses in their inner faces, the longitudinally extending bars having their end portions engaged in the slots of the cross bars and having their outer side faces formed with vertical recesses receiving portions of the cross bars having the vertical slots therein and their inner side faces formed with vertical recesses bordering the vertical recesses of the cross bars, vertical standards having lower portions fitting between the longitudinally extending bars and fitting tightly in the recesses of the longitudinally extending bars and the cross bars, and a rail extending between said standards and engaged therewith.

5 3. A clothes rack comprising a base having longitudinally extending bars spaced from each other and cross bars, the cross bars having vertical slots leading from their upper edge faces, the longitudinally extending bars having end portions fitting into the slots and formed with vertical extending recesses receiving portions of the cross bars bordering the slots to provide interlocking engagement between the longitudinally extending bars and the cross bars, vertical standards having lower end portions fitting tightly between the longitudinally extending bars against inner side faces of the cross bars and a rail mounted on and extending between said standards.

10 4. A clothes rack comprising a base having longitudinally extending bars spaced from each other and cross bars, the cross bars having vertical slots leading from their upper edge faces, the longitudinally extending bars having end portions fitting into the slots and having outer side faces formed with recesses receiving portions of the cross bars and thereby interlocked with the cross bars, standards having lower ends fitting 15 between the longitudinally extending bars and having side portions fitting into recesses formed in inner side faces of the longitudinally extending bars and thereby interlocked therewith, and a rail mounted on and extending between said standards.

20 5. A clothes rack comprising a base having transversely spaced longitudinally extending bars and cross bars having means removably interlocked with end portions of the longitudinally 25 extending bars, vertical standards having lower end portions fitting between the longitudinally extending bars against the cross bars, inner faces of the cross bars and the longitudinally extending bars being formed with companion recesses 30 forming seats, and fitting into the seats formed by the companion recesses and thereby interlocked with the longitudinally extending bars and the cross bars, and a rail extending between and removably connected with said standards.
